SYRINGE HOLDER

Attilio Marcelli, Plainview, Ill.

Application July 21, 1949, Serial No. 106,036

10 Claims. (Cl. 128—218)

1

The present invention relates in general to hypodermic syringes, and more particularly to certain new and useful improvements in holders for hypodermic syringes to facilitate filling and discharge thereof.

Users of hypodermic syringes are frequently patients who require regular, daily self administration of medicinal preparations. Such persons often have great difficulty in reading the small and somewhat obscure calibrations on the glass barrels of conventional hypodermic syringes and are constantly subjected to the hazard of making mistakes which can be serious or even fatal. The problem of providing some automatic stop means which will assist such persons in the loading of their syringes is complicated by the fact that the plunger of a syringe must be withdrawn preliminarily to fill the barrel of a syringe with a volume of air somewhat larger than the volumetric size of the dose to be withdrawn from the ampule or vial. With such quantity of air in the barrel the syringe is plunged through the soft, penetal rubber stopper in the end of the vial or ampule and the air expelled into the vial so as to set up a slight amount of pressure upon the medicinal preparation therein contained. Thereupon, the needle is withdrawn slightly so that it is entirely immersed within the liquid and the plunger withdrawn, thereby sucking a quantity of the liquid medicinal preparation into the syringe barrel. In this operation, also, the syringe barrel is withdrawn to a point substantially beyond the dosage required and is then carefully pushed back returning a small quantity of the liquid medicinal preparation to the ampule or vial until the precise dosage is contained within the syringe. This procedure is considered highly important so that there will be no accidental inclusion of air bubbles within the liquid to be administered, otherwise the patient may suffer from an embolism which can conceivably be fatal. This manipulative technique makes it necessary that any non-visual means for gauging the final quantity of the dose in the syringe must be arranged so as to become operative after all of the preliminary steps have taken place and will function at the time that the plunger is pushed back to reduce the quantity of liquid in the syringe to the precise and correct dosage desired.

The primary object of the present invention is to provide a syringe holder of the type stated which incorporates an adjustable arm for coaction with the syringe plunger to facilitate drawing the correct dosage into the syringe so as to obviate the necessity for reading the graduations directly on the syringe itself.

A further object of the present invention is to provide a syringe holder of the type stated which is adapted for removable engagement with a vial-holding member.

2

A further object of the present invention is to provide a syringe holder of the type stated which embodies automatic means for injecting the needle into the user's flesh and an adjustable needle guard for assuring that the needle will be properly positioned before injection.

An additional object of the present invention is to provide a syringe holder of the type stated which is reliable and durable in use and economical in construction.

With the above and other objects in view, my invention resides in the novel features of form, construction, arrangement, and combination of parts presently described and pointed out in the claims.

In the accompanying drawings (two sheets)—

Figure 1 is a front elevational view of a syringe holder constructed in accordance with and embodying the present invention showing a hypodermic syringe in operative position therein;

Figure 2 is a transverse sectional view taken along line 2—2 of Figure 1;

Figure 3 is a fragmentary rear elevational view;

Figure 4 is a fragmentary vertical sectional view illustrating the syringe in retracted position;

Figures 5, 6, and 7 are transverse sectional views taken along lines 5—5, 6—6, and 7—7, respectively, of Figure 2;

Figure 8 is a fragmentary front elevational view of a modified form of syringe holder constructed in accordance with and embodying the present invention;

Figure 9 is a fragmentary side elevational view of the modified form of syringe holder; and

Figure 10 is a perspective view of a clip for maintaining the hypodermic syringe removably within the modified form of holder.

Referring now by reference characters to the drawings which illustrate practical embodiments of the present invention, A designates a conventional hypodermic syringe having a cylindrical barrel 1, fabricated preferably of glass, being open at its upper end and provided at its lower end with an outlet nozzle or tip 2 over which is frictionally engaged the hub 3 of a hypodermic needle 4. At its upper end the barrel 1 is provided with an integral collar or shoulder 5 and upon its outwardly presented face, said barrel 1 is provided with suitable graduated markings 6 for indicating the amount of dosage. The drawings herein, for purposes of illustration, show a graduation in 40 units as commonly marked on syringes used by diabetic patients for injection of insulin. Slidably disposed within the barrel 1 and projecting at its upper end therebeyond is a plunger or piston 7 having a diametrically decreased neck portion 8 and an enlarged head 9.

Provided for use with a syringe A is a syringe

holder 10, fabricated preferably of stainless steel, or other suitable light metal, comprising an upper relatively narrow tubular sleeve 11 having an inside diametral size suitable for freely accommodating the syringe barrel 1. Secured, as by rivets, at the upper end of the sleeve 11 is a plurality of spaced flexible finger elements 12 for gripping engagement upon the collar 5 for retentively securing the syringe A within the holder 10. At its lower end the sleeve 11 is integrally provided with a flange 13 against the upper face of which bears the lower end of a compression spring 14 surroundingly positioned about the lower portion of the sleeve 11 and bearing at its upper end against the under face of a closure disk 15. The disk 15 is marginally threaded for engagement with the internally threaded upper end of a lower sleeve 16 disposed outwardly of, and in concentric relation to, the upper sleeve 11. The sleeve 16 is diametrically decreased, as at 17, to provide an abutment shoulder 18 upon which is normally seated the flange 13 of the upper sleeve 11. The lower portion of the sleeve 16 is internally threaded for engagement with the external threads of a ferrule 19 upon which is also engaged a knurled locking collar 20. The lower end portion of the ferrule 19 is provided with a pair of diametrically opposed, L-shaped bayonet slots 21 for lockingly receiving pins or bayonets 22 suitably secured to, as by soldering, and projecting outwardly from a tubular member 23. Mounted upon the tubular member 23 adjacent its lower end are opposed outwardly extending lugs 24, 24', for swingably supporting a vial-holding frame 25 by extension through the apertured upper ends 26, 26', respectively, thereof. The lower transverse section 27 of the frame 25 is centrally provided with an axially bored, internally threaded boss 28 for receiving an upwardly threaded thumb screw 29. Disposed within the frame 25 is a conventional type vial or bottle 30, such as an insulin-containing ampule, with its neck 31 extending upwardly into the tubular member 23 and provided with a conventional rubber stopper 32 having a relatively thin, easily punctured center 33 for facile penetration by the needle 4. The screw 29 may be adjusted to bring its upper end into tight abutting engagement against the bottom face of the ampule 30 to maintain it securely within the frame 25.

It will thus be seen that through the concentricity of the sleeves 11, 16, the ferrule 19 and the tubular member 23, the needle 4 will be in axial alignment with the center 33 of the ampule stopper 32.

Pivots mounted on the face of the upper portion of the sleeve 16 is a latch member 34, its lower end being beveled and turned inwardly in the formation of a tongue 35 which is biased by a spring 36 for normally projecting through an aperture 37 in the wall 38 of the sleeve 16. Diametrically opposed to the aperture 37 in the sleeve wall 38 is an internally threaded, relatively small aperture 39 for engagement with the threaded end of a screw 40 having an enlarged, smooth-surfaced neck 41 and a relatively large head 42. The neck 41 of the screw 40 projects through a suitable aperture in the lower end of a channel-shaped support arm 43 for pivotally supporting the same, and has encirclingly disposed about its face a coil spring 44 which abuts at its inner end against the sleeve wall 38 and at its outer end against the inwardly presented face of the arm 43. The upper end of the arm 43 is of sufficient

length to extend beyond the upper end of the sleeve 11 when said arm 43 is swung into upward position (see Figure 2). Provided in the arm 43 is an elongated, longitudinal slot 45, through which outwardly projects a threaded lug 46 suitably secured, as by soldering, at its inner end to a slide arm 47 disposed within the channel of the support arm 43, and projecting outwardly thereof at its upper end which is bent perpendicularly and laterally inwardly, as at 48, to form a stop member 49, having an arcuate recess 50 in one of its side margins for normal abutment against the stem and neck portions of the plunger 7 (see Figure 5).

Threadedly engaged on the outer projecting end of the lug 46 is an adjustment nut 51 for maintaining the slide arm 47 in any selected position relative to the support arm 43, it being apparent that the limits of adjustment are determined by the length of the slot 45. Suitably marked or delineated upon the outwardly presented face of the slide arm 47 is a graduated scale 52 in calibration with the particular scale provided upon the barrel 1 of the syringe A, for purposes appearing more fully hereinafter.

In usage, the vial-holding frame 25 with the ampule 30, containing the particular matter desired, as insulin, is positioned upon the lower end of the ferrule 19 by lockingly engaging the pins 22 within the slots 21. The syringe A is then inserted downwardly in the syringe holder 10 and held securely therein by the gripping engagement of the fingers 12 upon the shoulder 5, in which position, the needle 4 will penetrate the center of the stopper 32 and extend into the fluid in the ampule 30. The slide arm 47 is then adjusted so that the scale 52 thereon will be set in relation to the upper margin of the support arm 43 (see Figure 1) to indicate the required dosage. Thereon the nut 51 is tightened for maintaining the slide arm 47 securely in the selected position. The support arm 43 is then pivoted to prevent the stop member 45 from interfering with the substantial outward movement of the plunger 7 for drawing material from the ampule 30 into the barrel 1. Upon the completion of the outward movement of the plunger 7, the support 43 is then swung to bring the stop member 49 into abutment against the stem of the outwardly drawn plunger 7. The plunger 7 is then pushed inwardly until the under face of the head 9 abuts against the upper face of the stop member 49, whereon the contents in the barrel 1 will be in the requisite amount. It will be noted that the excess material expelled by the syringe A upon the inward movement of the plunger 7 into abutting contact with the stop member 49 will return to the ampule 30, thereby effecting a marked economy. By use of the slide arm 43, the user need not watch closely the scale or graduations upon the barrel 1 each time the syringe A is filled, since once the slide arm 47 has been appropriately set, it may be used continuously without any further checking of the scale. This feature is of extreme importance to habitual users with affected eyesight, such as diabetic sufferers who utilize hypodermic, syringes daily, many of whom, as a natural result of their disease, frequently have impaired sight.

After the barrel 1 has been filled, as discussed above, the vial-holding frame 25 with the bottle 30 therein, is removed by disengagement of the pins 22 from the slots 21, and outward pulling thereof to dislodge and clear the needle 4 from the stopper 32. Thereon the user grips the upper

portion of the sleeve 11 and pulls upwardly for compression of the spring 14 (see Figure 4). In its upward travel, the flange 13 will be brought into contact with the tongue 35 of the latch 34, causing it thereby to rock outwardly for allowing the continued upward movement of the flange 13. Thereon the latch 34 will, through bias of the spring 36, be pivoted to swing the tongue 35 inwardly into abutment against the under face of the flange 13 to retain the spring 14 under compression. As shown in Figure 4, in this retracted position, the lower end of the needle 4 will be in elevated relation to the lower margin of the ferrule 19 which thus serves as a needle guard for engagement of the user's skin. The user then positions the syringe holder 10 so that the lower end of the ferrule 19 will define the field of the desired location upon his body for the injection. Therein the upper end of the latch 34, through finger pressure, is pivoted inwardly against the sleeve wall 33 to rock the tongue 35 outwardly from engagement with the flange 13 to release the spring 14, for effecting downward movement of the sleeve 11 which causes the needle 4 to enter the user's flesh. The plunger 7 is then pushed inwardly to discharge the dosage contained in the barrel 1, the support arm 43 having first been swung to remove the stop member 49 from contact with the plunger 7.

In order to control the amount of penetration of the needle 4 through the stopper 32 or in cases where a larger needle is used and it is necessary to assure its retraction above the lower margin of the ferrule 19 for facilitation of injection, the locking collar 20 may be loosened and the ferrule 19 threaded upwardly or downwardly, as necessary, the requisite distance, and maintained in such selected position by tightening of the collar 20.

If desired, a modified form of syringe holder 53 may be provided for use with a conventional hypodermic syringe A', having a barrel 1', nozzle 2', hub 3', needle 4', collar 5', graduations 6', and plunger 7' with a neck 8' and head 9', said syringe A' being in all respects similar to the syringe A above described. The holder member 53, comprises an elongated sleeve or tubular member 54 having a diametrically increased lower end portion 55 suitably provided with opposed outwardly projecting ears or lugs 56, 56', for extension through the apertured upper ends of a vial-holding frame 25', which is substantially similar to the vial-holding frame 25 above described. Retentively disposed in the frame 25' is an ampule 30' containing the desired medication, with its neck 31' disposed within the lower portion 55 of the sleeve 54, said neck 31' being provided with a stopper 32' having a thin, easily penetrated center 33'.

Extending longitudinally downwardly from the upper margin of the sleeve 54 is a recess 57 for revealing the graduated scale 6'. Opening into the recess 57 is a transversely extending recess 58 with a relatively wide mouth 59 for lockingly receiving the lower outwardly projecting end 60 of a clip member 61 integrally provided with a split band 62 for encircling the barrel 1' and a finger member 63 extending upwardly therefrom for grippingly engaging the collar 5' to retain the clip 61 in position upon the 70 syringe A'.

Pivottally secured upon the face of the sleeve 54 is a channel-shaped support arm 43' having engaged therein a slide arm 47' provided with a transversely extending upper end in the forma-

tion of a stop member 49' for optional abutting relationship against the stem of the plunger 7'. The support arm 43', and the slide arm 47' and their integral parts, are in all respects similar to the support arm 43 and slide arm 47, above described.

In usage, the syringe A' is inserted downwardly into the sleeve 54 with the lower end 60 of the clip 61 passing through the recess 57 until it has reached a point adjacent the mouth 59 of the recess 58. In this position, the needle 4' will have penetrated the center 33' of the stopper 32' with which it is axially aligned, a substantial distance into the ampule 30' for easy flow of the material therein through the needle 4', independent of its level. Thereon the syringe A' is turned to effect entry of the lower end 60 of the clip 61 into the recess 58 for retentively maintaining the syringe A' during filling thereof, which is accomplished by operation of the plunger 7', the slide arm 47' and stop member 49', in the same manner as described above in connection with the syringe A. It is apparent that the clip 61 will be so positioned on the syringe A' that when it is engaged in the recess 58, the graduations 6' of the barrel 1' will be viewable through the recess 57. After the requisite dosage has been drawn into the barrel 1', the syringe A' is then rotated to disengage the clip 61 from the recess 58 and is then withdrawn from the sleeve 54, with the stop member 49' maintained in contact with the head 9' to prevent any untoward inward movement of the plunger 7' during rotation. The syringe A' is thus in ready condition for injection purposes.

It should be understood that changes and modifications in the form, construction, arrangement, and combination of the several parts of the syringe holder may be made and substituted for those herein shown and described without departing from the nature and principle of my invention.

Having thus described my invention what I claim and desire to secure by Letters Patent is:

1. A holder for hypodermic syringes comprising an elongated tubular portion for receiving the barrel of the syringe, a support arm swingably mounted on the outer face of said tubular portion, a measuring arm in outwardly spaced relation to the syringe barrel mounted on said support arm for relative positionment with respect thereto, said measuring arm projecting at one end beyond the support arm, the projecting end of said measuring arm being provided with a transversely inwardly extending section for engagement with the head of the syringe plunger to limit the inward movement thereof for expulsion of air and excess material whereby the desired quantity will remain in the barrel, and means for maintaining said measuring arm in any selected position relative to the support arm.

2. A holder for hypodermic syringes comprising an elongated tubular portion, a support arm swingably mounted on said tubular portion, a measuring arm adjustably mounted on said support arm and projecting at one end therebeyond, the projecting end of said measuring arm being provided with a transversely inwardly extending section for engagement with the syringe plunger to limit the inward movement thereof, a graduated scale provided on the outwardly presented face of the measuring arm in calibration with the scale upon the barrel of the syringe, and means for maintaining said measuring arm in any selected position relative to the support arm.

3. In a holder for hypodermic syringes having a first sleeve, a second sleeve disposed at its lower end in said first sleeve and adapted for slidable movement therein, and a tubular needle guard adjustably mounted on the lower end of said first sleeve, the improvement comprising a vial-holding assembly detachably secured to said needle guard, said vial-holding assembly comprising a neck portion, a frame having opposed upper ends swingably engaged upon the neck portion, and means for maintaining a vial securely within the frame.

4. In a holder for hypodermic syringes having a first sleeve, a second sleeve disposed at its lower end in said first sleeve and adapted for sliding movement therein, a tubular needle guard adjustably mounted on the lower end of said first sleeve in concentricity with said first and second sleeves, and a locking collar engaged on said needle guard, the improvement comprising a vial-holding assembly comprising a neck portion adapted for detachable engagement upon the needle guard and being concentric therewith, a frame having opposed upper ends for swingable engagement upon the neck portion, and an adjustment screw provided in said frame for maintaining a vial securely therein.

5. In combination with a holder for hypodermic syringes having an elongated tubular member for receiving a syringe in concentricity therewith, a bail-like vial holding frame disposed outwardly of the lower end of said tubular member and being secured thereto, and a liquid-containing vial supported on said frame for normal extension of its head portion into the tubular member in concentricity with said syringe whereby the cap portion of said vial will be presented for puncture by the syringe needle.

6. In combination with a holder for hypodermic syringes having an elongated tubular member for receiving a syringe in concentricity therewith, a bail-like vial-holding frame disposed outwardly of the lower end of said tubular member and being secured thereto, a liquid-containing vial supported on said frame for normal extension of its head portion into the tubular member in concentricity with said syringe whereby the cap portion of said vial will be presented for puncture by the syringe needle, and means for rigidly securing said vial in position.

7. A holder for hypodermic syringes comprising an elongated tubular portion for receiving the barrel of a syringe, a support arm swingably mounted at its lower end on the exterior face of said tubular portion and being marginally in-turned to provide a slide way, a measuring arm slidably disposed within the slide way of the support arm for relative axial movement with respect thereto into extended position beyond the upper end of the support arm, said measuring arm having graduations provided on its outwardly presented face calibrated for correspondence to the barrel contents, a transversely extending arm integral with the measuring arm at its upper end for abutment against the under surface of the head of the plunger of the syringe to limit the inward movement thereof, and means for maintaining the measuring arm and support arm in selected position relative to each other.

8. A holder for hypodermic syringes having a barrel, said barrel having graduated markings for indicating contents of the barrel, a plunger movable in said barrel and a diametrically increased head on said plunger, comprising an elongated tubular portion for receiving the bar-

rel of the syringe, a channel-shaped support arm pivotally mounted at its lower end on the exterior face of said tubular portion for swingable movement in a plane parallel to the vertical axis of the syringe barrel, a measuring arm slidably disposed on said support arm for relative axial movement with respect thereto whereby said measuring arm may extend beyond the upper end of the support arm, graduations delineated on the outwardly presented face of the measuring arm in calibration with the graduated markings on the barrel so that the graduations on the measuring arm immediately adjacent the upper end of the support arm in any relative position therebetween will indicate the volumetric content of the barrel, set screw means for maintaining said measuring arm and support arm rigidly in selected relative position, and an abutment arm integral with the measuring arm at its upper end and extending transversely inwardly in axial normal relation to the axis of the plunger for movement into the path thereof for limiting its inward movement thereby assuring that the material contents of the barrel will be as indicated on the measuring arm graduations.

9. In combination with a holder for hypodermic syringes having an elongated tubular member for receiving a syringe in concentricity therewith and a vial containing material for withdrawal by the syringe, the improvement comprising a vial-holding frame having a lower transverse section and side sections, a tubular-shaped neck member for removable securement within the lower end of the tubular member of the holder, said side sections being pivotally mounted at their upper ends at diametrically opposed points on said neck member and a set screw threadedly engaged in the lower transverse section of the frame for extension upwardly therethrough whereby a vial supported on said frame will have its head maintained within the neck member for alignment with the syringe and secured therein by engagement on its under surface by the set screw.

10. In combination with a holder for hypodermic syringes having an elongated tubular member for receiving a syringe in concentricity therewith and a vial containing material for withdrawal by the syringe, the improvement comprising a vial-holding frame having a lower transverse section and a pair of upwardly projecting side sections, said side sections being spaced from each other a distance in excess of the diameter of the vial to be held therein, a tubular-shaped neck member for removable securement within the lower end of the tubular member of the holder, said side sections being pivotally secured on said neck member at diametrically opposed points whereby said frame will be swingable within the plane of the holder, said transverse section having a centrally disposed threaded bore, and a thumb screw threadedly engaged in said bore for extension upwardly therethrough into the interior of the frame whereby a vial disposed in said frame will have its head portion inserted within the lower end of the neck member for alignment with the syringe and being held snugly by engagement on its under surface by the thumb screw.

ATTILIO MARCELLI.
